UNITED STATES PATENT OFFICE.

FRANKLIN CHATFIELD, OF MINNEAPOLIS, MINNESOTA, ASSIGNOR TO NORTHWESTERN
KNITTING COMPANY, OF MINNEAPOLIS, MINNESOTA, A CORPORATION.

FABRIC-GUIDE FOR STITCHING-MACHINES.

1,144,811.

Specification of Letters Patent. Patented June 29, 1915.

Original application filed January 2, 1912, Serial No. 669,082. Divided and this application filed June 3, 1912. Serial No. 701,260.

To all whom it may concern:

Be it known that I, FRANKLIN CHATFIELD, of Minneapolis, Hennepin county, Minnesota, have invented certain new and useful
5 Improvements in Fabric-Guides for Stitching-Machines, of which the following is a specification.

The object of my invention is to provide
10 means for easily and quickly regulating the
distance of the line of stitches from the edge
of the fabric.

The invention consists generally in various
15 constructions and combinations, all as
hereinafter described and particularly point-
ed out in the claims.

In the accompanying drawings forming
part of this specification, Figure 1 is a view,
partially in section, illustrating the applica-
20 tion of my fabric guide to a stitching
machine, Fig. 2 is a side view, also partially
in section, showing the position of the fabric
guide with respect to the presser foot and
the mechanism for operating the guide, Fig.
25 3 is a plan view, showing the manner of
mounting the fabric guide on the machine,
Fig. 4 is a detail sectional view of the means
for adjusting the fabric guide, Fig. 5 is a
30 detail sectional view showing the means for
adjusting the guide toward and from the
presser foot, Fig. 6 is a sectional view on
the line x—x of Fig. 5.

In the drawing, 2 represents the frame of
the machine, and 3 the work table. 4 is a
35 needle, 5 the presser foot, and 6 the recipro-
cating hook which coöperates with the
needle to form the stitch. These parts are
all in use with the ordinary shell stitching
machine.

7 is a plate secured to the machine frame
40 and 8 is a second plate between which and
the plate 7 a guide-way is formed. In this
guide-way is a slide 10. A pin 11 is mounted
in the plate 7 and projects into an opening
45 12 in the slide 10 in which a spring 13 is
arranged. The compression of this spring
normally tends to hold the slide in its re-
tracted position against the pin 11, shown in
Fig. 4. A fabric guide 14 is mounted on the
50 slide 10 and provided with a rearwardly
projecting end 15 having a vertical slot 16
that is adapted to receive the laterally pro-
jecting pin 17 on the presser foot. This pin
bridges the gap between the presser foot and
the fabric guide and prevents the fabric and

the fuzz thereon from entering this gap 55
when the guide is set out, away from the
presser foot to increase the distance of the
line of stitches from the edge of the fabric.
When the fabric guide is set up against the
presser foot to decrease the distance of the 60
line of stitches from the edge of the fabric,
the pin 17 will enter the slot in the guide.
The compression of the spring 13 normally
tends to pull the guide away from the
presser foot and by means of the mechanism 65
hereinafter described the guide can be ad-
justed toward or from the presser foot
against the compression of this spring until
the desired bight of the stitches is obtained.

Various devices may be employed for op-
erating the fabric guide, but I prefer to pro-
vide the mechanism which I will now de-
scribe in detail. The plate 7 carries an out-
wardly projecting stud 18 supporting a
sleeve 19 that is slidable on said stud and 75
also adapted to rotate thereon and provided
at its inner end with a seat 20 between which
and a screw head 21 on the stud 18 a coiled
spring 22 is arranged. The compression of
this spring is evidently increased by moving 80
the sleeve outwardly on its supporting stud
and decreased when the sleeve is pushed in-
wardly. A plate 23 is mounted on the inner
end of said sleeve and has a split lower por-
tion provided with a clamp screw 24 for se- 85
curing the plate 23 on said sleeve. The
upper portion of said plate has a transverse
slot 25 to receive a pin 26 that is carried by
the slide 10 and projects outwardly through
a slot 27 in the plate 8. When, therefore, 90
pressure is applied to the pin 26 the slide 10
will be pushed outwardly to move the fabric
guide toward the presser foot to change the
distance of the line of stitches from the edge
95 of the fabric.

For the purpose of moving the pin 26 I
provide a sliding pin 28 movable lengthwise
in a socket in the upper portion of the plate
23 and having one end contacting with the
pin 26 and its opposite end engaged by a 100
lever 29 that is fulcrumed at 30 and has a
limited rocking movement. I prefer to pro-
vide a set screw forming a fulcrum for said
lever to allow adjustment thereof and a
locking screw 31 for holding the set screw in 105
place. The outer end of the sleeve 19 has a
finger grip 32 and upon said sleeve a collar
33 is mounted, having a finger grip 34. A

pin 35 is mounted on said collar and projects between the lever 29 and the plate 23, so that when the collar 33 is rotated, the pin 35 will be pushed between the lever 29 and the plate 23 to rock the said lever and force the pin 28 inwardly against the pin 26, or withdrawn from engagement with the lever 29 to allow the fabric guide spring to withdraw the fabric guide from contact with the presser foot and increase the distance of the line of stitches from the edge of the fabric, as shown in Fig. 4.

36 represents a ribbon guide having one end adjustably mounted by means of a set screw 37 in the upper portion of the plate 23. This ribbon guide forms the subject matter of an application filed January 2, 1912, Serial No. 669,082 of which this case is a division and detailed description and illustration herein will be unnecessary.

The plate 23 is provided at its lower end with a lug 37' that is adapted to enter into a notch 38 in a horizontal plate 39 secured to the plate 7 (see Fig. 6). This notch has a beveled edge 40, with which the lug contacts as shown in Fig. 6. When the lug enters the notch the lower portion of the plate 23 will be rocked on the stud 18 throwing the upper portion of said plate toward the presser foot and tilting the ribbon guide to its ribbon feeding position. When it is desired to swing the ribbon guide to an inoperative position the lug 37' is withdrawn from the notch 38 and allowed to slide along the edge of the plate 39 into a slot 39', the sleeve 19 sliding inwardly on the stud 18 and carrying the plate 23 with it and swinging the ribbon guide to an inoperative position.

40 I claim as my invention:—

1. The combination, with a stitching mechanism and a presser foot, of a sliding fabric guide, a slotted plate, a pin connected with said guide and projecting into said slot, a pin mounted in said plate and engaging said first named pin, a lever pivoted on said plate and bearing on said second named pin, a spring normally tending to retract said fabric guide and means for rocking said lever to actuate said pins and move said fabric guide toward said presser foot.

50 2. The combination, with a stitching

mechanism and a presser foot, of a spring retracted fabric guide, a stationary stud, a rotatable collar mounted thereon, a lever, means actuated by the movement of said lever for forcing said guide against the tension of said spring toward said presser foot, and a pin carried by said collar in position to engage and rock said lever.

60 3. The combination, with a machine frame, of a stitching mechanism and a presser foot, a guideway provided in said frame, a spring retracted slide movable in said guideway, a fabric guide carried by said slide, a rotatable member having a finger grip and means operatively connecting said rotatable member with said slide for forcing said fabric guide toward said presser foot.

70 4. The combination, with a stitching mechanism and a presser foot having a comparatively small, outwardly projecting pin thereon, a fabric guide having a shank at right angles substantially to said presser foot and an end portion that is bent rearwardly, parallel, substantially, with said presser foot and provided with a transverse slot adapted to receive the pin on said presser foot, a spring normally tending to retract said guide from said presser foot, and mechanism for forcing said guide toward said presser foot against the tension of said spring.

75 5. The combination, with a stitching mechanism and a presser foot having a comparatively small, outwardly projecting pin thereon, of a fabric guide having a shank at right angles substantially to said presser foot and adjustable toward and from the same, and an end portion that is bent parallel substantially with said presser foot and provided with a slot to receive the pin on said presser foot, a rotatable mechanism for forcing said guide toward said presser foot, and a spring device normally tending to retract said guide.

80 In witness whereof, I have hereunto set my hand this 16th day of May 1912.

FRANKLIN CHATFIELD.
